UNITED STATES PATENT OFFICE.

LEO SOLINGER, OF NEW YORK, N. Y., ASSIGNOR TO EAGLE PENCIL COMPANY, OF NEW YORK, N. Y.

DESIGN FOR A LEAD-PENCIL TIP.

No. 38,711.

Specification for Design.

Patented July 30, 1907.

Application filed June 22, 1907. Serial No. 380,372. Term of patent 14 years.

To all whom it may concern:

Be it known that I, LEO SOLINGER, a citizen of the United States, residing at New York, county of New York, State of New York, have invented a new, original, and ornamental Design for Lead-Pencil Tips, of which the following is a specification, reference being had to the accompanying drawing, forming part thereof.

Figure 1 is a front elevation of a lead pen-

cil tip, showing my new design. Fig. 2 is an elevation of the same from the rear.

I claim:

The ornamental design for a lead pencil tip, as shown.

LEO SOLINGER.
